UNITED STATES PATENT OFFICE

CHARLES F. ROOT, OF CLEVELAND, OHIO, ASSIGNOR TO THE CHANDLER & PRICE COMPANY, OF CLEVELAND, OHIO, A CORPORATION OF OHIO

SHEET TRANSFERRING MECHANISM FOR PRINTING PRESSES

Original application filed April 18, 1921, Serial No. 462,256. Divided and this application filed August 18, 1930, Serial No. 474,769.

The present improvements, relating, as indicated, to mechanism for feeding sheets to printing presses, have more particular regard to sheet feeding devices designed for use with so-called Gordon or platen printing presses. The peculiar difficulties involved in providing a satisfactory automatic sheet feed, (as well as sheet delivery) for presses of this type need not be detailed, being well understood. Such difficulties are further evidenced by the numerous attempts that have been made to provide devices of this sort, only a relatively small number of which have ever found even limited commercial use.

The object of the present invention is to provide a sheet feeding device that may be readily attached to existing presses with little or no alteration in their structure. The sheets are picked up by pneumatic suction and novel and improved means for controlling such suction conjointly with the movement of the picker fingers so as to locate the sheets accurately on the platen of the press constitute further features to which attention will be directed.

The present application constitutes a division of certain features set forth in my pending application Serial No. 462,256, filed April 18, 1921, these features relating especially to the novel construction of the paper engaging and moving devices or grips.

To the accomplishment of the foregoing and related ends, said invention, then, consists of the means hereinafter fully described and particularly pointed out in the claims, the annexed drawings and the following description setting forth in detail certain mechanism embodying the invention, such disclosed means constituting, however, but one of various forms in which the principle of the invention may be used.

In said annexed drawings:—

Fig. 1 is a side elevation of the upper portion of the so called Gordon type press showing my improved sheet engaging and moving devices as attached thereto, the press in this figure being shown in dotted outline only; Fig. 2 is a perspective view showing a portion of the structure of Fig. 1 on an enlarged scale; Fig. 3 is a vertical section through the im-

proved sheet engaging and moving device support as taken on line 3—3, Fig. 2; Fig. 4 is a longitudinal vertical sectional view through said sheet engaging and moving devices as taken on line 4—4, Fig. 2 looking in the direction of the arrows; Fig. 5 is a detailed sectional view taken on the longitudinal vertical plane through one of the sheet engaging and moving grips; and Fig. 6 is a similar detailed sectional view taken on line 6—6, Fig. 2.

The press illustrated in the drawings, as previously indicated, is of the familiar platen or Gordon type and need not be further described than to note the oscillatorily mounted platen 1 on which the sheet requires to be placed preliminarily to being brought into contact with the form by the conjoint movement of such platen and of the opposite bed 2, which carries such form in a suitable chase, not shown. In Fig. 1 of the drawings, the press is shown with the platen in its sheet receiving position, the grippers 3, whereby the sheet is held on to the platen during the printing operation, being suitably raised.

My improved feeding mechanism is preferably installed, as shown, on the left hand side of the main frame of the press, and requires, in addition to the suction fingers and operating mechanism therefor, only a suitable table or support 4 for the stack 5 of blank sheets. This table will be provided with suitable elevating mechanism, preferably automatic in character, whereby the upper surface of the stack 5 may be maintained at a substantially constant elevation. Various tables of this sort have been devised and are on the market, and since the construction of such table forms no part of the present invention, detailed illustration thereof has been omitted, as merely tending to confusion.

The main supporting member of the sheet feeding or transferring device consists of a tubular rod or shaft 10 that is rotatably supported in suitable bearings 11 attached at one side of the frame of the press, the upper of these bearings being shown only in Fig. 1. Said tubular shaft 10, as a matter of fact, is not directly mounted in the bearings 11, but lies within a telescoping tube 12, that is, in

addition to being rotatable in its bearings, capable of vertically reciprocable movement therein as well. This outer tube 12 terminates short of the upper end of the inner tube 10 to permit certain vertical reciprocatory movement of the outer tube to effect the raising and lowering of the sheet engaging and moving grips, this function being independent of the particular invention now claimed 10 and need not be gone into in detail.

Fixedly mounted on the upper end of tubular shaft 10 is a cap piece 14 provided with a radially projecting arm 15, and longitudinally aligned with the latter is a tubular extension 16 that is rotatively adjustably mounted therein. An inner tube 17 is in turn rotatably movable within said extension 16, its respective ends projecting beyond said extension 16 in the one case, and beyond the bracket 15 in the other, as best shown in Fig. 1. A hollow arm 18 is fixedly attached to the end of said member 17 thus projecting beyond tubular extension 16, said arm lying at right angles to said member, and having oscillatorily mounted in a suitable bearing at its extremity a transverse tubular shaft 19. As shown in Fig. 4, the tubular member 17 is formed so that its interior remains at all times, i. e., irrespective of any oscillatory movement of said member, in communication with the interior of tubular shaft 10 through cap piece 14 and bracket 15, subject only to the control of a valve. The transverse shaft 19 at the outer end of arm 18 will accordingly likewise be thus in connection at all times with the interior of said tubular shaft 10.

The sheet engaging and moving devices or grips, shown as two in number and in the form of suction tips or fingers, are carried 40 by tubular arms 21 that are attached to said shaft 19, extending therefrom in a reverse direction, i. e., so as to lie generally alongside of arm 18. Each of the tubular arms 21, as clearly shown in Fig. 5, is of angular form 45 and two-piece construction, the one piece 21^a depending downwardly from and being adjustably secured to the tubular shaft 19 by a clamp 21^a, whereby the angular position of the arm as a whole about said shaft may be 50 varied within limits, and the other piece 21^b of said arm 21 extending horizontally from and being adjustably secured to such first piece by a clamp 21^b, whereby angular position of this portion of the arm, together with 55 the suction tips 20 carried by it, may be varied in a horizontal plane about such first part as an axis. The suction tips 20, as shown, comprise portions 20^a that are longitudinally adjustably secured in the horizontal portions 60 21^b of the tubular arms 21 by means of clamp collars 22, whereby the effective length of the arms may be varied. As a result of the construction of the parts of the sheet-transferring mechanism just described, it will be 65 noted in the first place that by angularly ad-

justing the arms 21 about tubular shaft 19 through the medium of clamps 21^a, the suction tips may be brought into proper vertical position with respect to the stack 5 in the one case and to the platen 1 in the other, as indicated by the double-headed arrow *x*, Fig. 2. In the second place, by angularly adjusting the horizontal portions of the jointed arms 21 through the medium of clamps 21^b, the positions of the suction tips 20 may be independently varied in a direction transversely of the surface of the platen, as indicated by the double-headed arrow *y*, Fig. 2; and in the third place, by adjusting the suction tips longitudinally of the arms 21 through the medium of clamps 22, the positions of such tips may be independently varied from front to rear of the platen, as indicated by the double-headed arrow *z*, Fig. 2. In other words, it is possible to select a wide range of positions in both directions for each of the grips to contact with the platen, or rather with a sheet to be transferred, thus adapting the mechanism for use with sheets of irregular shape, cut-outs and the like.

Adjustably mounted on tubular member 16 is an arm 25 that is connected by means of a link 26 with a lever arm 27 on the aligned end of shaft 19. Actually, as best shown in Fig. 2, the arm 25 is adjustably mounted on member 16 in desired fixed angular position by means of set screw 25^a, and the same is true with respect to arm 27 which is adjustably mounted on shaft 19, adjustment in this instance being possible through the medium of clamps 25^b. As a result of this construction it will be seen that oscillation of tubular member 17 will be effective, not only to drop the outer end of tubular arm 18 and therewith the shaft 19, but also to rock said shaft 105 so as to vary the angular relation of the same, and thus of the tubular arms 21 that connect the suction fingers, to said arm 18. The effect of such rocking movement or oscillation of tubular member 17, in its supporting bracket 110 15, is best illustrated in Fig. 1, where the position of the parts, when the suction fingers are located over the stack 5 is shown in full lines, while their changed position where located over the platen 1 is shown in dotted outline. Variation in the angular adjustment of arm 25 on tubular member 16 serves to secure the same result as does the previously described angular adjustment of arms 21 about member 19 through the medium of 115 clamps 21^a; in other words, the normal position of the sucker tips in relation to the plane of the stack 5 and/or platen may be varied by either or both of these adjustments, it being noted that the first-named adjustments, 120 viz., of said arm 25 on member 16, serves to adjust both sucker tips simultaneously, while adjustment thereof through the medium of clamps 21^a may be independently made.

Upon referring to Fig. 1 (see also the per- 130

spective view of the sheet transferring mechanism in Fig. 2, which shows the parts in the same operative position, i. e., with the sucker tips 20 in contact with the upper most sheet 5 of stack 5), it will be seen that a lost motion connection is provided between arm 25 and the link 26 by having pivot pin 25^b work in a short slot 25^c. When the parts are in proper adjustment, this pin should, as illustrated, occupy an intermediate position in the slot when the sucker tips thus contact with a sheet, either on the stack or platen, such contact being then merely by gravity. Of course, during the swinging movement of arm 16, the pin 25^b will move to one end of the slot, viz., the left as shown in the figures last referred to.

Oscillation of tubular shaft 17 is secured by means of a lever 30 attached to its inner end, i. e., the end lying adjacent to cap piece 14, and a link 31 that connects the free end of said lever with the upper end of the outer tubular shaft 12 that surrounds inner shaft 10. A collar 32 on such upper end of shaft 12 provides means for thus attaching link 31 to the latter and also carries a pin 33 that lies parallel with the axis of the two shafts in question, and slidably engages an aperture in a laterally projecting lug 34 on cap piece 14. From the construction just described it will be seen that rotation of the outer shaft 12 will be effective to rotate the inner shaft 10 irrespective of the vertical position of said shaft 12, and that, conversely, reciprocation of shaft 12 and consequent oscillation of tubular shaft 17 may take place irrespective of the rotative position of the two shafts 10 and 12.

For the purpose of oscillating the two shafts 10 and 12 or for reciprocating the latter of said shafts, suitable mechanism is provided in connection with the operating devices of the press, the same being adequately described in my said copending application, and as forming no part of the present invention a detailed description or illustration thereof is deemed unnecessary. It is sufficient to say that the two shafts 10 and 12 are rotatable or oscillatory, and that the shaft 12 is capable of reciprocatory movement.

In the illustrated form of sheet engaging and moving devices, the paper grips are shown as suction tips and, of course, the entire sheet transferring device must be accommodated for conducting the vacuum line from a stationary point on the machine to such suction tips. In the several views illustrating in detail my improved sheet engaging and moving device there appears a vacuum line from the interior of the tubular shaft 10 in communication with the interior of the horizontal tubular member, which in turn at its outer end through suitable points in member 18, communicates with the interior of shaft 19, which may be connected at its lower end to any suitable source.

As has been described in detail, Figs. 5 and 6 clearly illustrate the communication between the interior of member 19 and suction tips 20. It should be mentioned that suction line leading through the shaft 10 and shaft 17 is subject to the control of a valve 61 shown in Figs. 3 and 4 carried by the cap piece 14. Such valve is shown only for the purpose of illustration and may be connected with the suction line as found most convenient, especially as it is sufficient for the purpose in hand to release the vacuum introduced in the picker fingers by the suction supplied through such shaft 10. The illustrative valve consists simply of a segmental member fitted to the periphery of a disk 62, in which there is a radial port 63 that communicates with the interior of tubular member 17, the latter being otherwise sealed, save for the openings in the ends of the picker fingers 20. Accordingly, when the valve closes the port 63 there will be an effective suction at the ends of said fingers, but upon opening said port by oscillating the valve to suitably clear the same, such suction effect is interrupted, as will be readily understood.

The mechanism thus provided by this invention is relatively simple and free from complications so that there is very little to get out of order. Moreover, the adjustments provided for the picker fingers enable the proper location or engagement of said fingers with the sheet to be moved, i. e., these fingers may be accurately adjusted so that they will engage with the selected point or points on the surface of the sheet to avoid, for instance, contact with the printing thereon or on the other hand, to accommodate irregularities in the shape of the piece being moved.

The present mechanism has been described without reference to any mechanical device for automatically removing the sheet from the platen after it has been printed. It should be noted, however, that a suitable timing of the valve controlling the suction and the proper location of the picker fingers so as to engage the sheet at its side or rear, rather than its forward edge, would constitute of the device herein disclosed a sheet delivery instead of a feed mechanism.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In sheet transferring mechanism for platen presses, a member movable toward and away from the platen, arms independently adjustable on said member, and grips, one for each arm, each grip being adjustable in its respective arm.

2. In sheet transferring mechanism for platen presses, a movable support, a member adjustable on said support, an arm adjustable in said member, and a grip adjustable in said arm, said grip serving to transfer sheets from sheet receiving position and adapted through said adjustments to be positioned to grasp sheets at various selected points.
- 10 3. In sheet transferring mechanism for platen presses, a member movable toward and away from the platen, a tubular arm adjustable on said member, and a grip for taking sheets from one position and depositing the same in another position, said grip being 15 slideable in said adjustable arm and adapted to engage sheets at various selected points.
4. In sheet transferring mechanism for platen presses, a movable member having a longitudinal suction bore therein, an arm adjustable on said member, the interior of said arm being in communication with the bore of said member in various positions of adjustment of said arm in said member, a suction grip adjustably mounted in said arm, 25 said grip being in communication with the interior of said arm in the various positions of adjustment of said grip in said arm.
5. In sheet transferring mechanism for platen presses, a movable support, members separately mounted on said support for adjustment about a pivotal axis, and adjustable grips carried in said adjustable members for grasping a sheet at points variously spaced 35 from and in various angular relations to said support.
6. In sheet transferring mechanism for platen presses, a movable support, a member mounted on said support for adjustment about an approximately horizontal pivotal axis, an arm carried by said member and adjustable in a plane approximately parallel with the platen of the press, and an adjustable grip telescopically carried in said arm.
- 40 7. In sheet transferring mechanism for platen presses, a movable support, a member mounted on said support for adjustment about an approximately horizontal pivotal axis, an arm carried by said member and adjustable in a plane approximately parallel with the platen of the press, and a grip telescopically carried in said arm and longitudinally adjustable thereof.
- 45 8. In sheet transferring mechanism for platen presses, a movable support, a member mounted on said support for adjustment about an approximately horizontal pivotal axis, an arm carried by said member and adjustable in a plane approximately vertical to the plane of the platen being jointed for angular adjustment in a plane approximately parallel with said platen, and an adjustable grip carried by said arm.
- 50 9. In sheet transferring mechanism for platen presses, a member movable toward and away from the platen, an arm carried by said member and angularly adjustable relatively thereto in a plane approximately vertical to the platen of the press and a second arm carried by said first arm, said second arm being adjustable in a plane approximately vertical to such first plane, and a grip telescopically carried in said second arm.
- 55 10. In sheet transferring mechanism for platen presses, a member movable toward and away from the platen, arms carried by said member and independently adjustable relatively thereto in a plane approximately vertical to the platen of the press and a second arm carried by each of said first arms, said second arms being adjustable in a plane approximately vertical to such first plane, and a grip carried by each of said second arms and adjustable longitudinally thereof.
- 60 11. In sheet transferring mechanism for platen presses, a tubular member movable toward and away from the platen, a hollow arm carried by said member and angularly adjustable relatively thereto in a plane approximately vertical to the platen of the press, a second arm carried by said first arm and a grip communicating with the center of said arm carried by said second arm and adjustable therein.
- 65 12. In sheet transferring mechanism for platen presses, a member movable toward and away from the platen, arms carried by said member and independently angularly adjustable relatively thereto in a plane approximately vertical to the platen of the press, a second arm carried by each of said first arms and a grip carried by each of said second arms and adjustable longitudinally thereof.
- 70 13. In sheet transferring mechanism for platen presses, a member movable toward and away from the platen, an arm carried by said member and angularly adjustable relatively thereto in a plane approximately vertical to the platen of the press, said arm being jointed to a second arm for angular adjustment of said second arm in a plane approximately parallel to such platen, and a grip telescopically carried in said second arm.
- 75 14. In sheet transferring mechanism for platen presses, a member movable toward and away from the platen, an arm carried by said member and angularly adjustable relatively thereto in a plane approximately vertical to the platen of the press, said arm being jointed to a second arm for angular adjustment of said second arm in a plane approximately parallel to such platen, and a grip telescopically adjustably carried in said second arm.
- 80 15. In sheeting transferring mechanism for platen presses, a member movable toward and away from the platen, an arm carried by said member and angularly adjustable relatively thereto in a plane approximately vertical to the platen of the press, said arm being jointed to a second arm for angular adjustment of said second arm in a plane approximately parallel to such platen, and a grip telescopically adjustably carried in said second arm.

- vertical to the platen of the press, said arm being jointed to a second arm for angular adjustment of said second arm in a plane approximately parallel to such platen, and 5 a grip telescopically adjustable in said second arm.
16. In sheet transferring mechanism for platen presses, a support movable toward and away from the platen, a member extending from said support in the general direction of movement thereof, a second rigid member extending transversely of said first member adjacent the outer end thereof, and a grip indirectly carried by said second member and 10 adjustable in a plane approximately parallel to the platen of the press to grasp a sheet at various selected points.
17. In sheet transferring mechanism for platen presses, a support movable toward and 20 away from the platen, a member extending from said support in the general direction of movement thereof, a second member extending transversely of said first member adjacent the outer end thereof, and means including 25 grips carried by said second member, said grips being independently adjustable in a plane approximately parallel to the platen of the press to grasp a sheet at various selected points.
- 30 18. In sheet transferring mechanism for platen presses, a support movable toward and away from the platen, a member extending from said support in the general direction of movement thereof, a second member extending transversely of said first member adjacent the outer end thereof, arms attached to 35 said second member so as to be angularly adjustable relatively thereto in a plane approximately vertical to the platen of the press, and means including a grip carried by each of said arms.
19. In sheet transferring mechanism for platen presses, a support movable toward and away from the platen, a member extending from said support in the general direction of movement thereof, a second member extending transversely of said first member adjacent the outer end thereof, arms attached to 45 said second member so as to be angularly adjustable relatively thereto in a plane approximately vertical to the platen of the press, and a grip carried by each of said arms, said grips being adjustable relatively thereto.
- 50 20. In sheet transferring mechanism for platen presses, a support movable toward and away from the platen, a member extending from said support in the general direction of movement thereof, a second member extending transversely of said first member adjacent the outer end thereof, arms attached to 55 said second member so as to be angularly adjustable relatively thereto in a plane approximately vertical to the platen of the press and other arms attached to said first-named arms so as to be adjustable in a plane parallel to 60 such first plane, and a grip carried by each of said second-named arms.
21. In sheet transferring mechanism for platen presses, a support movable toward and away from the platen, a member extending 70 from said support in the general direction of movement thereof, a second member extending transversely of said first member adjacent the outer end thereof, arms attached to said second member so as to be angularly 75 adjustable relatively thereto in a plane approximately vertical to the platen of the press and other arms attached to said first-named arms so as to be adjustable in a plane parallel to such first plane, and a grip carried by each 80 of said second-named arms and adjustable longitudinally thereof.
22. In mechanism of the character described, the combination with a horizontally extending support, of a member oscillatorily 85 mounted on said support so as to be movable in a plane lying transversely of the latter, and a second member provided with a sheet engaging and moving finger, said second member being oscillatorily mounted in turn 90 on said first member about an axis removed from the latter's axis of oscillation and extending reversely from its own axis toward the latter's axis.
23. In mechanism of the character described, the combination with a support movable in an approximately horizontal plane, of a member oscillatorily mounted on said support so as to be movable transversely of 95 the latter in a general vertical direction, and a second member provided with a sheet engaging and moving finger, said second member being oscillatorily mounted in turn on said first member, about an axis removed 100 from the latter's axis of oscillation.
24. In mechanism of the character described, the combination with a support movable in an approximately horizontal plane, of means including a pneumatic suction device carried by said support, said device being bodily movable transversely thereof in 110 a plane substantially at right angles to the plane of said support.
25. In mechanism of the character described, the combination with a support movable in an approximately horizontal plane, of means including a pneumatic suction device oscillatorily mounted on said support to be bodily movable transversely thereof in 115 a plane substantially at right angles to the plane of said support.
26. In mechanism of the character described, the combination with a support movable in an approximately horizontal plane, 125 of means including a member oscillatorily mounted on said support to be movable transversely thereof, and a suction device oscillatorily mounted in turn on said member so as to be bodily movable in a plane substan- 130

tially at right angles to the plane of said support.

27. In mechanism of the character described, the combination with a platen, of a suitable support disposed to lie above said platen in the sheet receiving position of the latter, a member mounted on said support so as to be oscillatory about an approximately horizontal axis, and a sheet engaging and moving device carried by said member and bodily movable relatively to the support in a direction transverse of the axis of oscillation of said member.

28. In mechanism of the character described, the combination with a platen of a suitable support disposed to lie above said platen in the sheet receiving position of the latter, a member mounted on said support so as to be oscillatory about an approximately horizontal axis, and a sheet engaging and moving device carried by said member and oscillatory with respect to the support about an axis removed from the axis of oscillation thereof.

29. In mechanism of the character described, the combination with a platen, of a suitable support disposed to lie above said platen in the sheet receiving position of the latter, a member mounted on said support so as to be oscillatory about an approximately horizontal axis, and means including a sheet engaging and moving finger carried by said member and oscillatory with respect to the same about an axis removed from but parallel with the axis of oscillation thereof.

30. In mechanism of the character described, the combination with a platen of a sheet engaging and moving finger, and means for movably supporting same, said means including two members located above said platen in the sheet receiving position of the latter, one of the said members being carried by the other, and one having an oscillatory path of travel while the other is bodily movable in a direction transverse of the axis of oscillation of said first member.

31. In mechanism of the character described, the combination with a horizontally extending support, of a member oscillatorily mounted on said support so as to be movable transversely of the latter in a general vertical direction, and a second member provided with a sheet engaging and moving finger, said second member being oscillatorily mounted in turn on said first member about an axis removed from the latter's axis of oscillation.

32. In mechanism of the character described, the combination with a horizontally extending support, of a member oscillatorily mounted on said support so as to be movable in a plane lying transversely of the latter, and a second member provided with a sheet engaging and moving finger, said second

member being oscillatorily mounted in turn on said first member about an axis removed from the latter's axis of oscillation.

Signed by me this 9th day of August, 1930.
